UNITED STATES PATENT OFFICE.

ARTHUR E. SEXTON, OF LOS ANGELES, CALIFORNIA.

PAPER-HOLDER.

No. 813,594.

Specification of Letters Patent.

Patented Feb. 27, 1906.

Application filed December 26, 1903. Serial No. 186,782.

To all whom it may concern:

Be it known that I, ARTHUR E. SEXTON, a citizen of the United States, residing at Los Angeles, in the county of Los Angeles and 5 State of California; have invented a new and useful Paper-Holder, of which the following is a specification.

This invention relates to certain improvements in holders for dispensing toilet-paper and the like, in which the sheets are interfolded, each sheet being centrally folded to form two leaves and each leaf being interlaced with the corresponding leaves of the sheets both above and below it. The holder is provided with a discharge-slot in its side, top, or bottom, and the arrangement of the sheets is such that on the withdrawal of one sheet the succeeding sheet will be partly withdrawn and held projected in the slot in convenient 20 position to be grasped and withdrawn.

The principal object of the invention is to so construct the discharge-plate as to facilitate the withdrawal of the sheets of paper, the plate being located at or forming either 25 the side or top or bottom of the holder. These slotted discharge-plates are usually so constructed as to present a broad flat surface for contact with the paper, and the sheets have but little space in which to bulge, as a 30 sheet being withdrawn moves a succeeding sheet to discharging position. To overcome this difficulty, I make the central portion of the plate with an outward bulge or curve to form a recess and broaden the throat or entrance-space to the discharge-slot, thus forming 35 a space in which the paper may more readily bulge during the withdrawing operation.

A further object of the invention is to contract the width of the discharge-slot in order 40 that the paper may be held out in a more direct line, the edge of the sheet being projected at substantially a right angle to the plane of the discharge-plate, and this is rendered 45 possible by the enlarged or broadened throat of the slot, as hereinafter described.

A still further object of the invention is to facilitate the withdrawal of sheets which may not be fully projected by forming a 50 notch or depression in each wall of the slot, so that the user may more readily grasp the sheet.

A still further object of the invention is to provide for the projection of the paper in

case of failure of the feed by means of one or 55 more feeding-rollers, having knobs outside the casing to permit convenience in turning.

A still further object of the invention is to improve and simplify the construction of holders having top discharge-openings by providing for the adjustment of the stress of the spring as the latter becomes gradually fatigued from constant use.

With these and other objects in view, as will more fully hereinafter appear, the invention consists in the novel construction and arrangement of parts hereinafter described, illustrated in the accompanying drawings, and particularly pointed out in the appended claims, it being understood that various 65 changes in the form, proportions, size, and minor details of the structure may be made without departing from the spirit or sacrificing any of the advantages of the invention.

In the accompanying drawings, Figure 1 is 75 a perspective view of a toilet-paper holder constructed in accordance with the invention. Fig. 2 is a detail sectional view of the same, drawn to an enlarged scale and illustrating the position which the sheets generally assume during the withdrawing operation. Fig. 3 is a view of a modified form of discharge-plate. Fig. 4 illustrates a slight modification of the notched slot-walls shown in Fig. 1. 80

Similar numerals of reference are employed to indicate corresponding parts throughout the several figures of the drawings.

The holder forming the subject of the present invention is designed to contain sheets of 90 toilet-paper or the like in which each sheet is folded in half to form two leaves, the fold-lines of alternate sheets being disposed in opposite directions and the two leaves of each sheet being interlaced with the similar leaves 95 of the sheets on each side.

In the drawings, 10 indicates a suitable holder formed of sheet metal or other material and adapted to contain the interfolded sheets, which are fed by suitable means in the 100 direction of a discharge-slot 11. The walls of the slot are extended in order that a sheet of paper partly withdrawn may be held projected at an angle to the general plane of a plate 12, in which said discharge-slot is 105 formed.

In holders previously constructed by me the plate 12 extended for its full width in a

plane parallel with the plane of the sheets and offered an extensive surface for frictional contact with said sheets during the withdrawing operation. The discharge-slot of each holder was formed directly in the plate 12, and to permit the bulge of the paper without turning it became necessary to form the slot of considerable width, and the edge of the projected sheet could not be held a sufficient distance from the surface of the plate to be conveniently grasped by the user. To overcome these difficulties and to arrange for the necessary room for the bulging of the paper without binding or tearing, the plate 15 is provided with an outward bulge or curve forming a recess 13, the walls of which may be arranged on either straight lines, as shown in Fig. 2, or on curved lines, as shown in Fig. 3. From edge to edge of the recess is approximately one-third of the entire width of the plate, and during the withdrawing of the sheet the sheet being withdrawn and the next succeeding sheet will generally assume the position shown in Fig. 2, the recess affording sufficient space for the paper to bulge, while the remaining portion of the sheet beyond the edges of the recess afford sufficient frictional resistance to the sheets to prevent the withdrawal of more than one sheet at a time. By arranging the recess in this manner I am enabled to materially reduce the width of the discharge-slot, and the extended walls of the latter serve to project the sheet in such manner that it may be conveniently 35 grasped and withdrawn.

In some cases, owing generally to some defect in the paper, a sheet will not be fully projected, and its withdrawal could not be accomplished with convenience owing to the extended or thickened walls of the discharge-slot. To overcome this difficulty, each wall is provided with a notch, as shown in Fig. 1, and the notches are preferably about the center of the length of the slotted walls, so that 45 the thumb and finger may be conveniently inserted to grasp the sheet, and the tractive force will be more evenly distributed than if the notches are formed at either end of the slot. This feature of the invention could also be applied without change to the discharge-slots where the walls are formed by comparatively thick strips of wood or similar material, as indicated at 16 in Fig. 4.

In cases where the slotted discharge-plate 55 forms the top of the paper-holder and the paper is fed outward toward the discharge-point by means of a spring the fatigue of the spring will lessen its stress under constant use, and it has been found during the course of many experiments that in order to secure a uniform service some provision must be made for adjusting the spring in order to maintain the impelling force constant.

In Fig. 2, 17 indicates a plate forming a support for the bottom of the bundle of paper

and under this plate is a coiled compression-spring 18, that tends to force the paper upward in the direction of the discharge-slot. When there is a large quantity of paper in the holder, the spring will be under greatest compression, and therefore exercise the greatest force, although the friction between the uppermost sheet of paper and the inner surface of the discharge-plate will remain practically the same at all times, owing to the fact that the weight of the paper decreases constantly as sheet after sheet is withdrawn, and the force exerted by the spring is correspondingly lessened, owing to its increased length. When the holder is first placed in service and the spring is new, the sheets will be properly held against the slotted discharge-wall of the holder. After being in use for some time the spring will become fatigued and will no longer be able to press the paper with sufficient force in the direction of the discharge-slot. When this occurs, one or more plates 20 of thin metal are placed on top of the paper-holding plate in order by increasing the weight of the spring and increasing the extent of its compression to restore the efficiency of said spring.

The delivery-slot is preferably extended to one or to both of the side walls and continued downward in said walls in such manner as to expose the upper sheets of paper, as shown in Fig. 1, so that a pencil-point or similar implement may be readily inserted to catch the side edge of the upper sheet for withdrawing the first sheet when a fresh supply of paper has been added to the holder.

In order to reduce the frictional contact between the vertical walls of the holder and the paper, and thereby permit a more delicate adjustment of the paper-feeding means, a number of rods 21 are employed in order to prevent contact between the edges of the sheets and the inner surfaces of the walls of the holder, or suitable ribs or corrugations may be employed in place of said rods, as will be readily understood.

In some cases it may happen that the paper will not feed properly, especially when beginning to use a fresh supply of paper, and in order to compensate for this disadvantage a pair of rollers 23 are arranged at the top or other discharge-plate. The rollers are held in suitable bearings in such manner that a portion of their peripheries will extend through slots 24 in the casing and engage the sheets of paper at points on opposite sides of the delivery-slot. These rollers are preferably provided with roughened peripheries in order to more firmly engage with the paper, and near one end of each roller is a turning-knob for the convenience of the user.

Under ordinary circumstances the rollers will rotate as idlers without interfering with the discharge of the paper, and should the paper fail to feed from any cause or at the

commencement of the feeding the user may cause the topmost sheet to project from the slot by turning one or both of the rollers.

Having thus described the invention, what is claimed is—

1. In a holder for interfolded paper, a slotted discharge-plate having a recess forming an enlarged throat for the slot, and means for forcing the paper into contact with the inner surface of said plate.
2. In a holder for interfolded paper, a discharge-plate extending outward to form a recess into which the paper may bulge and having a discharge-slot the walls of which are extended outward to hold the sheets projected at an angle to the plate.
3. In a holder for interfolded paper, a plate having a discharge-slot, the walls of which are of greater area than the thickness of the plate and serve to hold the sheets projected at an angle to said plate, there being finger-notches formed in said walls.
4. In a holder for interfolded paper, a casting having a top discharge-slot, a paper-supporting plate, a spring exerting upward pressure on the plate, and a plurality of removable weight-plates carried by said paper-supporting plate.
5. In a holder for interfolded paper, a cas-

ing including a wall having a discharge-slot, 30 and a pair of rollers arranged one on each side of the slot for independent engagement with the sheets of paper.

6. In a holder for interfolded paper, a casting having a discharge-slot and provided with 35 auxiliary slots or openings on each side thereof, and auxiliary feeding-rolls having portions of their peripheries extending through the auxiliary slots and adapted for independent engagement with the sheets of paper. 40

7. In a holder for interfolded paper, a casting having a discharge-slot, and a pair of rollers disposed one on each side of the slot and adapted respectively to feed the paper in opposite directions toward said slot. 45

8. In a holder for interfolded paper, a casting having a discharge-slot, and a pair of rollers having roughened peripheries, said rollers being disposed one at each side of, but beyond the walls of the slot, said rollers having 50 terminal operating-knobs.

In testimony that I claim the foregoing as my own I have hereto affixed my signature in the presence of two witnesses.

ARTHUR E. SEXTON.
